Primary Examiner — L. Martinez(74) Attorney, Agent, or Firm — Charles McCloskey(57) CLAIM

The ornamental design for a bracelet for a watch, as shown and described.

DESCRIPTION

FIG. 1 is a top view of a bracelet for a watch showing our new design;

FIG. 2 is a side view thereof;

FIG. 3 is a bottom view thereof;

FIG. 4 is a side view thereof;

FIG. 5 is a front view thereof;

FIG. 6 is a back view thereof; and,

FIG. 7 is a top perspective view thereof.

The broken line areas show portions of the bracelet for a watch that form no part of the claimed design.

1 Claim, 2 Drawing Sheets(56)
